GEORGE L. POWNALL, OF ATLANTA, GEORGIA

ARTIFICIAL ICE MAKING APPARATUS

Application filed June 12, 1929. Serial No. 370,201.

My invention relates to improvements in artificial ice making apparatus. One of its objects is to provide improved apparatus whereby a greater weight of ice may be 5 frozen in a specified freezing space within a specified period. Another object is to materially reduce the first cost and renewals of the freezing equipment. Another object is to provide improved freezing apparatus 10 adapted to freeze from the exterior walls of a can or container inwardly, and means employed for a portion of the freezing period and operation to freeze from the interior toward the walls of the container. Another 15 object is to provide improved apparatus adapted to freeze from the exterior walls of a can or container inwardly and from the interior of the container outwardly for a portion 20 of the freezing period and to remove the interior freezing apparatus and complete the freezing operation from the exterior walls inwardly to close the core spaces and produce solid ice blocks. Another object is to provide 25 improved freezing apparatus adapted to freeze from the exterior walls of a can or container inwardly and from the interior outwardly covering a portion of the freezing 30 operation and to remove the interior freezing apparatus and withdraw the unfrozen water from the core space and refill the core 35 space and the space left by removal of the internal freezing apparatus, and then finish the freezing operation from the exterior of the container to form a solid ice block. An 40 other object is to provide an improved raw-water freezing apparatus adapted to freeze from the exterior walls of a can or container inwardly and from the interior outwardly covering a portion of the freezing operation, employing agitating means to free the ice from gas bubbles and impurities or foreign matter, and to remove the interior freezing apparatus, discharge the impurities and core-water, and refill the core space and the space 45 left by removal of the interior freezing apparatus, and completing the freezing operation from the exterior to form a solid ice block substantially free from impurities and imprisoned gas bubbles. My invention also 50 comprises certain details of form and ar-

rangement and combination of components, all of which will be fully set forth in the description of the accompanying drawings, in which:

Fig. 1 is a plan of an ice freezing tank or 55 unit embodying my improvements.

Fig. 2 is a perspective view of a detachable brine circulating pipe connection, detached.

Fig. 3 is a perspective view of another 60 brine circulating pipe connection, detached.

Fig. 4 is a perspective view of another 65 brine circulating pipe connection, detached.

Fig. 5 is a vertical section through the tank or unit shown in Fig. 1, being taken on line 5—5 of Fig. 1.

Fig. 6 is a perspective view of one of the 70 interior freezing members detached.

Fig. 7 is a central vertical section through 75 one of the stationarily mounted freezing cans before the interior freezing member is detached, taken on line 7—7 of Fig. 1.

Fig. 8 is a view similar to Fig. 7 after the 80 interior freezer member has been removed and showing a completed ice block.

Fig. 9 is a view similar to Fig. 7, illustrating 85 a modification in which a detachable ice can is employed.

Fig. 10 is a view similar to Fig. 9 after the 90 interior freezing member has been detached, and showing a completed ice block.

Fig. 11 illustrates a modification of Fig. 6. 95

The accompanying drawings illustrate 100 embodiments of my invention in which tank 15 represents a freezing tank or freezing tank unit of the raw-water type, in which tank 85 are either permanently or detachably located a series of ice cans or ice molds 16. The side walls of said ice cans are in contact with the brine contained in the freezing tank 15. The lower ends of the ice cans are seated over 90 openings 17 through the bottom of the tank 15. Pipe connections to the bottom of the ice cans provide for supplying precooled fresh water through a pipe line 18 to refill all the ice cans in a designated tank unit 15 95 at one operation. Air under pressure is supplied to the lower portion of each ice mold through an air supply pipe 20 and a series of air exit ports 21. The air is permitted to bubble up through the fresh water in the 100

ice cans to thereby agitate the fresh water and detach any gas bubbles or foreign matter from the surface of the ice as it is forming to thereby insure the formation of clear transparent ice. A drain pipe 22 enables the core-water to be drained from the cores of the partially formed ice blocks carrying therewith any impurities which may have accumulated therein, such as gases, salts, sediment or other foreign matter liable to detract from the quality or appearance of the completed ice block. After the impure core-water has been drained away, the core spaces are adapted to be refilled with fresh water from the fresh water supply pipe 18. If desired the core spaces may be refilled with pre-cooled distilled water, either by means of a separate water supply pipe not shown or through the pipe 18 from a storage tank of distilled water.

Mounted centrally of each ice can and forming substantially a partition to divide the ice can temporarily into two sections is an interior freezing member 24, which preferably comprises a closed sheet metal chamber which extends from the bottom of the ice can at its lower end to a position slightly above the rim of the ice can at its upper end. The chamber within the freezing member 24 is relatively narrow, and preferably terminates a short distance above the bottom of the ice can. A brine inlet tube 25 is sealed into the top wall of the freezing member 24 and extends downwardly within the chamber 35 of the freezing member 24 to near the bottom of said chamber, and its lower end held against displacement by a strap 98. The upper end of the tube 25 is flanged to form a coupling seat. A detachable brine supply pipe 28 is provided with a central coupling member 29 detachably attached to a coupling member 30 of a permanently located branch brine supply pipe 31. At each end of the pipe 28 is an elbow the free end of which is 45 provided with a coupling member 26 adapted to be detachably coupled to the upper end of the tube 25 by means of cam shaped arms 81 carried by a lever 82 which pivots upon a cross pin carried by the freezing member 24 close to the upper end of the tube 25. The arms 81 engage studs 83 carried by the elbow 26 to couple the pipe 28 to the tube 25. The middle section of the pipe 28 has a coupling member 29 which is attached detachably to a coupling member 30 of a permanently located brine supply pipe 31. A series of brine supply pipes 31 are attached to a brine header 32, and said pipes 31 are each located between two rows of ice cans, along the upper 55 edge of one of the frame timbers 33, and below the ice can lids 34. Each supply pipe 28 is adapted to be connected centrally to a coupling member 30 of a pipe 31, while opposite ends of said pipe 28 are connected to the 60 inlet ends of two tubes 25, to supply brine 65

to two freezing members 24, located in adjacent ice cans.

Each freezing member 24 is provided with a brine overflow tube 36 sealed into the wall thereof and adapted to permit brine to overflow into the brine tank 15, through a hole 38 bored through one of the frame timbers 37. If desired the overflow tubes might be connected detachably to return brine conduits in place of being allowed to overflow into the 75 brine tank. Each brine inlet tube 25 leads downwardly inside the freezing member 24 and terminates near the bottom of the chamber within the freezing member 24, so as to feed cold brine to the lower portion of the 80 chamber in said freezing portion of the member 24, while the warmer brine overflows from the upper portion of the chamber in the freezing member 24 through the overflow tube 36, and thereby causes ice to build up on the exterior of the freezing members 24 and to grow from the center of the ice can toward the exterior of the ice cans to thereby meet the ice forming upon the side walls of the ice cans and growing therefrom inwardly. 85 This freezing from the side walls inwardly and from the freezing member 24 outwardly causes the ice to form and practically fill the ice cans in about one-fourth of the time required to freeze the contents of the ice cans 90 when freezing from the exterior only. When the freezing has progressed from the exterior and from the interior member 24 until nearly all the water has been frozen, leaving only two small core spaces 40 and 41 located upon opposite sides of the freezing member 24, the supply of cold brine to the header 32 and brine pipes 31 is cut off and a supply of relatively warmer brine is fed through the header 32 and pipes 31 into the chamber of the freezing members 24, until the freezing members 24 are released from the ice blocks. 95 The supply of warm brine to the header 32 and pipes 31 is then cut off, and a suction pump or equivalent means is attached in 100 place of a force pump to the header 32 and pipes 31, which serves to withdraw all or part of the brine from the freezing members 24 down to the lower ends of the brine supply tubes 25. The freezing members 24 may then 105 be detached from the pipe members 28 connecting them to the brine pipes 31, without danger of introducing brine into the interior of the ice cans, and a crane chain may be hooked into the eyes 42 of the freezing members 24 to lift the freezing members 24 out of the ice cans. The core spaces are drained of any impure core-water before the internal 110 freezing members are detached. Either distilled water or raw fresh water, which has been pre-cooled, is supplied to the cans in sufficient quantity to fill the core spaces, and also to fill the space left upon removal of the freezing member 24, after said freezing member 24 has been detached. The freezing op- 115 120 125 130 135

eration is then continued for a further relatively short period, until the water in the core spaces and in the space from which the freezing member 24 was removed has become 5 solidified into a solid ice block. A hook or eye or other member for attaching the ice block to a crane hook for use in harvesting the ice may be introduced into the core spaces, or 10 into the space left by the removal of the freezing member 24, and frozen into the block if desired.

After the block of ice has solidified, warm brine is introduced to replace the cool brine in the freezing tank 15, to release the ice 15 blocks from the side walls of the ice cans, and the ice blocks are lifted from the ice cans and stored for use. The freezing members 24 are then replaced and the ice cans refilled with fresh water, ready to commence a new 20 freezing operation. Fresh raw-water may be employed, or distilled water, or the ice blocks may be formed partly from raw water and partly from distilled water.

In the modification Figs. 9 and 10, I have 25 shown my improvements applied to an ordinary detachable ice can instead of to a stationary or fixed raw-water type of freezing tank unit. As illustrated in Fig. 9 the interior freezing member 50, corresponding to the 30 freezing member 24 of Figs. 1 and 5, is mounted in a detachable ice can 51, and the ice can immersed in the brine of a brine tank, and the freezing operation allowed to proceed until the contents of the can 51 has solidified 35 with the exception of the two small core spaces 52 and 53, which contain the impure core-water. This core water is withdrawn by means of a suction pump, and flexible connection, and the freezing member 50 detached and 40 removed. The core spaces 52 and 53 and the space left by removal of the freezing member 50 are then filled with clean fresh water, and the freezing operation continued until the ice can is filled with a solid block of ice as 45 shown in Fig. 10, whereupon the can and ice block may be withdrawn from the brine tank and the ice loosened and harvested in the usual way, and the can returned to the brine tank for a new operation. It will be noted 50 that the freezing member 24 or 50 occupies a minimum amount of space, and hence requires a relatively small volume of water to refill the space from which it is removed, thereby providing for freezing the water employed to refill this space in a relatively short 55 period of time after refilling, due to the relatively small amount of freezing required and a reserve of negative energy stored in 60 the nearly completed ice block.

In order to hold the internal freezing members in place within the ice cans at their lower ends I preferably provide channels 64 centrally across the bottoms of the cans 16, 65 into which the lower ends or fins of the mem-

bers 24 enter to retain the members 24 in place.

It will be noted that the water in the chambers 66 below the bottom of the cans 16 is shielded from the refrigerant partly by 70 means of a heat insulator, for instance a body of asphaltum 65 occupying the bottom of the tank below the line of the can bottoms, and hence after the impure core-water has been withdrawn and the internal freezing members 75 have been withdrawn these core spaces and withdrawal spaces are in communication at their lower ends, and also communicate with the unfrozen water in the chambers 66 below the can bottoms so that all these spaces 80 may be refilled from the pipes 18 and chambers 66 at one operation. By draining the impure core water before releasing the internal freezing members, no impure core water enters the withdrawal spaces.

In the modification Fig. 11 in place of extending the brine inlet pipe down to the lower end of the internal freezing member 62 corresponding to the members 24 of Fig. 5, a 90 central partition 63 is inserted in the interior chamber of the internal freezing member 62 and the brine circulated down around the lower end of said partition 63 and thence to the outlet member 36. The member 62 is 95 otherwise similar to the member 24.

By or through the use of my improved freezing apparatus I am enabled to produce a designated weight of ice employing one-fourth of the freezing space and equipment as heretofore generally employed, due to the freezing operation proceeding from the interior outwardly as well as from the exterior inwardly, and to provision of means for conveniently and reliably carrying the operation forward, such as agitating the unfrozen water, the removal of the core-water, the withdrawal of brine from the interior freezing member, the release of the interior freezing member, and the convenient supply of brine to said interior freezing member.

The apparatus herein shown and described is capable of considerable modification within the scope of the claims without departing from the spirit of my invention.

What I claim is:

1. In combination a container for a body of water to be frozen provided with a transverse channel across the bottom thereof an internal freezing member detachably mounted in said container and in engagement with said transverse channel to position said internal freezing member relative to said container, means to circulate a freezing medium to and from said internal freezing member, said freezing member being tapered inwardly and downwardly from the upper end toward the lower end of the container and adapted to be detached and removed from the container before the freezing operation is completed.

2. In combination a container for a body of water to be frozen having a non-freezing zone at the bottom thereof exposed to the atmosphere and a conduit through which water and air may be introduced into said container, means to apply a refrigerant exteriorly to the side walls of said container, an internal freezing member means at the top of the container whereby said internal member is detachably seated in said container during a portion of the freezing operation and adapted to be detached and removed upwardly from said container before the freezing operation has been completed, said internal freezing member causing a core space to be formed within the container at each side thereof each communicating with said non-freezing zone at the lower end thereof, and a removal space formed by the removal of said internal freezing member communicating at its lower end with said non-freezing zone.
3. An artificial ice making container to hold a body of fresh water to be frozen and to have a refrigerant applied externally to the walls thereof, said container having a channel traversing the bottom thereof adapted to engage the lower end of an internal freezing member mounted in said container and detachable and removable upwardly from said container.
4. In an ice making apparatus the combination of an ice can, of means submitting a freezing medium to the exterior walls of said can and providing a non-freezing zone at the bottom of the can, the bottom of the can being exposed to the atmosphere, conduit means through which supply water and agitating air are admitted to the can and through which core water is drained therefrom, an internal freezing member removable from the top of the can and adapted upon admission of a freezing medium thereto to effect freezing from the interior of the can outwardly simultaneously with the freezing from the exterior inwardly for providing a removal space and a core water space on each side thereof and evacuation through said conduit means and subsequent filling through said conduit means.
5. As a new article of manufacture an internal freezing member for use with ice making apparatus comprising a downwardly tapering hollow partition-like member for insertion in an ice can, means providing for the circulation of a freezing medium therein, and a fin member extending across the edge thereof and providing a relatively non-freezing extension on the bottom of said member.

60 In testimony whereof I have affixed my signature.

GEORGE L. POWNALL.
